UNITED STATES PATENT OFFICE.

JOHN FRITSCHIE, OF PHILADELPHIA, PENNSYLVANIA.

DESIGN FOR A PUZZLE-BOARD.

SPECIFICATION forming part of Design No. 33,099, dated August 21, 1900.

Application filed July 18, 1900. Serial No. 24,115. Term of patent 3½ years.

To all whom it may concern:

Be it known that I, JOHN FRITSCHIE, a citizen of the United States, residing in the city and county of Philadelphia, State of Pennsylvania, have invented and produced a new and original Design for a Puzzle-Board, of which the following is a specification, reference being had to the accompanying drawings, forming part thereof.

10 The leading feature of my design for a puzzle-board is a field having side channels, an intermediate channel, and a peripheral channel, the intermediate channel leading to the side and peripheral channels.

15 Figure 1 represents a plan view of a puzzle-board embodying my design. Fig. 2 represents a vertical section thereof on line *x-x*, Fig. 1.

In the drawings, A designates a puzzle-board, on the field B of which are the walls C, which are somewhat loop-shaped, forming the channels D, the intermediate channel D', and the peripheral channel D². The channel D' communicates with the channels D, as at C', and with the channel D², as at C².

Having thus described my invention, what I claim as new, and desire to secure by Letters Patent, is—

The design for a puzzle-board substantially as shown and described.

JOHN FRITSCHIE.
